UNITED STATES PATENT OFFICE.

WILLIAM H. GROVER, OF BAY SHORE, NEW YORK.

DRIP DEVICE.

1,339,195.

Specification of Letters Patent.

Patented May 4, 1920.

Application filed October 24, 1919. Serial No. 333,089.

To all whom it may concern:

Be it known that I, WILLIAM H. GROVER, a citizen of the United States, and a resident of Bay Shore, in the county of Suffolk and 5 State of New York, have invented a new and Improved Drip Device, of which the following is a full, clear, and exact description.

This invention relates to improvements in 10 drip devices, and more particularly to a device for dripping fruit and the like in the manufacture of jelly, an object of the invention being to provide a drip device which will be entirely sanitary, which will protect the drip from contact with dust, dirt 15 or insects and which will most efficiently perform the functions for which it is intended.

A further object is to provide a device 20 of the character stated, which can be conveniently located at any point desired, which will support the assembled elements of the device in operative position, and which can be folded and packed or stored 25 in a small space when not desired for use.

A further object is to provide a device of 30 the character stated, which can be used without the necessity of the operator staining his or her hands by contact with the fruit or juice thereof.

With these and other objects in view the invention consists in certain novel features of construction, and combinations and arrangements of parts, as will be more fully 35 hereinafter described and pointed out in the claims.

In the accompanying drawings—

Figure 1 is a perspective view illustrating 40 my improved device in operative position;

Fig. 2 is a view in longitudinal section on the line 2—2 of Fig. 1; and

Fig. 3 is a perspective view showing the parts in folded position.

1 represents a ring supported on any desired number of legs 2, the latter being preferably connected to the ring 1 by means of hinges 3. The ring 1 and the legs 2, above referred to, may constitute a tripod, but, of course, the invention is not limited to the 50 particular number of legs.

Each leg 2 is provided on its inner face with a hook 4 and a platform 5 is provided with perforated lugs 6 to engage over the hooks 4 and hold the platform in position 55 and maintain the legs in their extended po-

sitions, thereby forming a strong and rigid support.

The platform 5 is preferably of two halves connected by hinges 5' so as to allow the platform to be folded when not in use, and 60 the legs 2, above referred to, swing inwardly so that they will occupy but small space when collapsed.

A drip pan 7 is supported on the platform 5 and a drip bag 8 is supported by the 65 ring 1. The upper end of the drip bag is positioned through an opening 9 of ring 1 and at its open end is provided with a series of eyes 10 adapted to be positioned over headed screws 11 or other suitable 70 devices secured to the ring 1. A protecting casing 12 open at both ends is also projected through the opening 9 and is provided with eyes 13 to engage over the headed screws 11. The lower end of the 75 casing 12 is positioned around the drip pan 7 and secured thereon by means of a draw string 14.

The bag 8 and the casing 12 may, of course, be of any suitable material, but I 80 preferably employ a white fabric which can be readily washed and restored to normal conditions after use.

A funnel 14' is projected through the 85 opening 9 within the upper end of the drip bag 8 and frictionally engages the fabric bag 8 and casing 12 to form a tight junction of the parts. The casing 12 is provided with tapes 15 which may be secured around the legs 2 to hold the casing away from the 90 bag 8, and a tape 16 may be secured to one of the legs so as to hold the legs in folded or collapsed position when the device is not in use, as shown in Fig. 3.

In Fig. 3 the casing 12 is shown secured 95 within the ring 1, but ordinarily this casing may be removed from the ring, but this is entirely for the user to decide.

The operation is as follows: The fruit or other material to be dripped is poured 100 through the funnel 14' into the bag 8 and will drip through the bag 8 into the pan 7. Any suitable covering may be positioned over the funnel 14' to prevent the passage of dust, dirt, and insects into the funnel, 105 and the casing 12 will prevent dust, dirt, insects, etc., to come in contact with the bag 8 or with the drip so that the device may be set aside and allowed to stand for the necessary length of time to insure a com- 110

plete dripping operation without any danger of dirt or unsanitary objects coming in contact with the drip.

When the dripping operation is ended, 5 the pan 7 can be removed and emptied and returned to the platform 5. After the funnel 14' is removed, the bag 8 can be disconnected from the screws 11 and with its pulp dropped into the pan 7 and conveniently removed to any place desired for discharge. The construction therefor prevents the necessity of handling the stained bag 8, which would result in staining the fingers of the operator, and the entire operation 10 can be conveniently carried out in a clean and sanitary manner.

Various slight changes may be made in the general form and arrangement of parts described without departing from the invention, and hence I do not limit myself 15 to the precise details set forth but consider myself at liberty to make such changes and alterations as fairly fall within the spirit and scope of the appended claims.

25 I claim:

1. A drip device of the character stated, comprising a support having an opening therein, a receptacle adapted to be positioned on the support below the opening, a drip bag secured in the opening above the receptacle, and a casing surrounding the bag and the upper end of the receptacle.

2. A device of the character stated, comprising a support having an opening therein, a receptacle positioned on the support below the opening, a drip bag having its open upper end in said opening and located above the receptacle, and a casing having its upper end projected through the opening 30 and its lower end secured around the receptacle.

3. A device of the character stated, comprising a support having an opening therein, a receptacle on the support below the opening, a drip bag having its upper open end in the opening and its lower end located above the receptacle, a casing positioned around and spaced from the bag, the upper end of said casing projected through said 45 opening and the lower end of said casing secured around the receptacle, and a removable funnel projected through said opening and frictionally binding the bag and casing against the walls of said opening.

55 4. A device of the character stated, comprising a support having an opening therein, a receptacle on the support below the opening, a drip bag having its upper open end in the opening and its lower end located

above the receptacle, a casing positioned 60 around and spaced from the bag, the upper end of said casing projected through said opening and the lower end of said casing secured around the receptacle, headed devices on the support adjacent the opening, 65 and eyes carried by the bag and the casing adapted to be removably positioned over said headed devices.

5. A device of the character stated, comprising a support having an opening therein, 70 a receptacle on the support below the opening, a drip bag having its upper open end in the opening and its lower end located above the receptacle, a casing positioned around and spaced from the bag, the upper 75 end of said casing projected through said opening and the lower end of said casing secured around the receptacle, headed devices on the support adjacent the opening, 80 eyes carried by the bag and the casing adapted to be removably positioned over said headed devices, and a funnel projected into the bag and frictionally binding the bag and the casing against the walls of said opening.

6. A device of the character stated, comprising a ring, legs hingedly connected to the ring and supporting the ring, a platform 85 removably connected to the lower portion of the legs and adapted to receive a receptacle 90 thereon, a casing, a drip bag projected through the opening of the ring, and a removable funnel normally within the open upper end of the drip bag.

7. A device of the character stated, comprising a ring, legs supporting the ring and hingedly connected thereto, a platform comprising two members hingedly connected, inwardly projecting hooks on the legs, perforated lugs on the platform engaging the 95 hooks, headed devices on the upper face of the said ring, said headed devices adapted to support a drip bag and a casing, and said platform adapted to support a drip pan.

8. A device of the character stated, comprising a ring, legs supporting the ring, a platform supported by the legs below the ring, a receptacle on the platform, a fabric casing projected at its upper end through the ring and at its lower end secured around the receptacle, devices at the sides of the casing removably securing the intermediate portion of the casing to said legs, a drip bag having its open upper end located in the opening and supported by the ring, and a removable funnel located in the open upper 100 end of the drip bag.

WILLIAM H. GROVER.
